UNITED STATES PATENT OFFICE.

LEWIS N. DAVIS, OF AKRON, OHIO.

REVERSIBLE STEAM ENGINE.

Application filed January 24, 1922. Serial No. 531,394.

To all whom it may concern:

Be it known that I, LEWIS N. DAVIS, a citizen of the United States, residing at Akron, in the county of Summit and State 5 of Ohio, have invented certain new and useful Improvements in Reversible Steam Engines, of which the following is a specification.

The invention relates to steam engines in 10 which the valve is controlled by an eccentric; and the object of the improvement is to operate the engine valve for both directions of motion of the crank shaft with a single eccentric, and without the use of a 15 shifting link.

The object of the invention is attained by 20 locating an eccentric ring around the crank shaft at one side of a hub which may be a part of the fly wheel; by securing the ring on a rock shaft journaled in the hub alongside of the crank shaft so that the center of the ring may be swung or shifted to one side or the other of the center of the crank shaft, and by providing means for turning the 25 rock shaft and locking it in various positions with reference to the crank shaft.

An embodiment of the invention is illustrated in the accompanying drawings, forming part hereof, in which—

30 Figure 1 shows the improvement applied to an upright, stationary engine;

Fig. 2, a side elevation of a portion of the engine;

Fig. 3, an elevation section of the same;

35 Fig. 4, an end view of the cam control means;

Fig. 5, a plan of the cam control sleeve;

Fig. 6, a plan of a modified form of the same; and

40 Fig. 7, a diagrammatic view illustrating the two extreme positions of the eccentric ring.

Similar numerals refer to similar parts throughout the drawings.

45 An eccentric ring 8 surrounding a rotary shaft 9, which may be and preferably is the crank shaft of the engine, is secured to a rock shaft 10 journaled in the hub 11, which may be and preferably is part of the fly

50 wheel 12 and is keyed upon the rotary shaft; so that the rock shaft is located along the side of and parallel with the rotary shaft.

The eccentric ring is preferably located at 55 one end of the hub and is keyed to one end

of the rock shaft which protrudes from the same end of the hub; and upon the other end of the rock shaft which protrudes from the other end of the hub, is secured a rock sleeve 13, upon the outer end of which diverging rock arms 14 extend astride the crank shaft.

A shifting sleeve 15 is feathered upon the rotary shaft alongside the rock sleeve, and is provided with cam wings 16 located and 65 shaped in reverse position, the edges of which abut the inner sides of the rock arms at or near the ends thereof, for swinging the same one way or the other with reference to the center of the rotary shaft. 70

For smaller engines, a simple form of cam wings may be used, as shown in Fig. 5, in which one rock arm rests on a flat seat 17 at the high end of one wing while the other arm rests upon a flat seat 17' at the 75 lower end of the other wing; from which seats the cam edges are inclined toward reversely positioned seats 18 and 18' at the other end of the wings; and it is evident that by sliding the shifting sleeve 16 endwise on the rotary shaft, the rock arms 14 will be operated to turn the rock shaft in its journal in the hub of the fly wheel.

An endwise movement of the shifting sleeve may be given by a lever 19 having a 80 yoke 20 on its end engaging trunnions 21 on a ring 22 swiveled on the end of the sleeve; which arms may be mounted on one end of a rock shaft 23 having an operating arm 24 on its other end in well known 85 manner.

The parts are so arranged that when the rock shaft is turned by the cam wings to the full extent in one direction, the eccentric ring will be in one operative position 95 shown by full lines, in Fig. 7, with the center 25 at one side of the center 26 of the rotary shaft; and when the rock shaft is turned by the cam wings to the full extent in the other direction, the eccentric ring will 100 be swung to the other operative position, shown by broken lines in Fig. 7, with the center 25' at the other side of the center of the rotary shaft.

The dotted circle in Fig. 7 indicates the 105 orbit of the center of the eccentric ring in its rotation around the center of the rotary shaft, and the dotted arc of a circle shows the portion of the orbit which the center of the eccentric travels when shifting from one 110

operative position to the other; the differential between said arc and the center of the driving shaft representing one half of the valve travel.

5. For larger engines a compound form of cam flanges may be employed, as shown in Fig. 6, wherein each flange has differential seats at each end to control the shut off in well known manner; thereby serving the 10 same purpose as the second notch in the quadrant of the ordinary engine. In this compound form, the sleeve 15' is provided with the cam wings 16' located and shaped in reverse position, the stepped flat seats 15 17^a and 17^b being provided at the high end of one wing and the stepped seats 18^a and 18^b at the low end thereof. Similar stepped seats 18^{a'} and 18^{b'} are located at the high end of the other wing and the stepped seats 20 17^{a'} and 17^{b'} at the low end thereof.

An eccentric strap 27 is journaled around the periphery of the eccentric ring, and an eccentric rod 28 extends from the strap and is pivotally connected to the valve stem 29, 25 operating endwise in the guide bracket 30 for operating the engine valve in well known manner.

I claim:

1. In an engine, a rotary shaft with a bearing secured on one side thereof, a rock shaft journaled in the bearing alongside the rotary shaft, an eccentric around the rotary shaft, rock arms on the rock shaft and means operating on the rock arms for turning the rock shaft to shift the eccentric into different positions.

2. In an engine, a valve, a rotary shaft with a bearing secured on one side thereof, a rock shaft journaled in the bearing alongside the rotary shaft, an eccentric around the rotary shaft secured to the rock shaft, an eccentric strap on the eccentric operatively connected with the valve, rock arms on the rock shaft and means operating on the rock

arms for turning the rock shaft to shift the eccentric into different positions.

3. In an engine, a valve, a rotary shaft with a hub secured thereon, a rock shaft journaled in the hub alongside the rotary shaft, an eccentric around the rotary shaft secured to the rock shaft, an eccentric strap on the eccentric operatively connected with the valve, rock arms on the rock shaft, and means operating on the rock arms for turning the rock shaft to shift the eccentric into 55 different positions.

4. In an engine, a valve, a crank shaft with a hub secured thereon, a rock shaft journaled in the hub alongside the crank shaft, an eccentric around the crank shaft secured to the rock shaft, an eccentric strap on the eccentric and operatively connected with the valve, rock arms on the rock shaft and means operating on the rock arms for turning the rock shaft to shift the eccentric into 65 different positions.

5. In an engine, a valve, a crank shaft with a fly wheel secured thereon, a rock shaft journaled in the fly wheel alongside the crank shaft, an eccentric around the crank shaft secured to the rock shaft, an eccentric strap around the eccentric operatively connected with the valve, rock arms on the rock shaft and a shift sleeve feathered on the rotary shaft having cam wings operating on 75 the rock shaft for turning the rock shaft to shift the eccentric into different positions.

6. In an engine, a rotary shaft with a bearing secured on one side thereof, a rock shaft journaled in the bearing alongside the 80 rotary shaft, an eccentric around the rotary shaft secured to the rock shaft, rock arms on the rock shaft astride the rotary shaft and a shifting sleeve feathered on the rotary shaft having cam wings thereon operating on the 85 rock arms for shifting the eccentric into different positions.

LEWIS N. DAVIS.
